BULKHEAD DOOR

Joseph J. Mascuch, Newark, N. J., and Alexis S. Gorshkoff, New York, N. Y., assignors to Breeze Corporations, Inc., Newark, N. J., a corporation of New Jersey

Application January 17, 1935, Serial No. 2,152

8 Claims. (Cl. 114—117)

This invention relates to closures and particularly to bulkhead doors and hatch covers for use on maritime vessels such as warships. In the construction of vessels, and particularly fighting vessels such as warships, a large number of bulkhead doors and hatch covers are used to separate compartments from one another. The weight of the doors is an appreciable factor in the weight of the vessel in view of the large number of doors used. It is necessary to provide doors of relatively great strength to withstand the stresses of service. Accordingly, one object of this invention is to provide a bulkhead door or hatch cover of great strength and rigidity, but which will be extremely light in weight with relation to its strength.

It has been common practice to form such doors of solid metal. This gives the desired strength but greatly increases the weight. A specific object of this invention is to provide a door formed of two relatively thin panels having a re-inforcing member therebetween.

It is desirable to have the doors and hatch covers airtight and watertight so that upon being closed one or more compartments may be effectively sealed. A further object of the invention is to provide a light weight door which will be airtight and watertight even though the air or water be under pressure.

A further object of this invention is to provide such a door or closure member fabricated entirely from stainless steel. A further object of this invention is to provide a closure member, the parts of which may be joined into a homogeneous whole entirely by welding in order to eliminate the use of removable securing elements such as rivets, bolts, screws, etc.

The invention consists of the combination, construction and arrangement of parts, as hereinafter illustrated, described and claimed.

In the accompanying drawings, forming part hereof, is illustrated one form of embodiment of the invention, in which drawings similar reference characters designate corresponding parts, and in which:

Figure 1 is a front elevation of a bulkhead door, partly broken away, to show the interior construction;

Figure 2 is a side elevation, partly in section, taken approximately on line 2—2 of Figure 1, looking in the direction indicated by the arrows;

Figure 3 is an enlarged horizontal section, partly broken away and partly in elevation, taken approximately on line 3—3 of Figure 1, looking in the direction indicated by the arrows;

Figure 4 is an enlarged fragmentary detail in horizontal section, taken approximately on line 4—4 of Figure 1, looking in the direction indicated by the arrows, and illustrating the handles of the door;

Figure 5 is an enlarged fragmentary detail in horizontal section, taken approximately on line 5—5 of Figure 1, looking in the direction indicated by the arrows, and illustrating the means to retain the door in closed position;

Figure 6 is an enlarged fragmentary detail in horizontal section, taken approximately on line 6—6 of Figure 1, looking in the direction indicated by the arrows, and illustrating the air pressure test vent;

Figure 7 is a plan view of a hatch cover, partly broken away, to show the interior construction;

Figure 8 is an enlarged vertical section, partly broken away and partly in elevation, taken approximately on line 8—8 of Figure 7, looking in the direction indicated by the arrows;

Figure 9 is a plan view of a modified form of hatch cover, partly broken away, and partly in section, taken on line 9—9 of Figure 10, looking in the direction indicated by the arrows;

Figure 10 is an enlarged fragmentary detail in vertical section, taken approximately on line 10—10 of Figure 9, looking in the direction indicated by the arrows.

Referring to the drawings, 11 designates the front panel or "skin" of the closure member, whether the closure member be door or hatch cover. The panel 11 is relatively thin and is preferably made of stainless steel, as are all of the metal parts hereinafter described. The front panel 11 is slightly longer and wider than a complementary rear panel 12. The panels 11 and 12 are separated by a corrugated re-inforcement 13. The corrugated member 13 may be made in one piece but for ease of handling in the fabrication of the door, it may be made in sections. The panels 11 and 12 are secured to the member 13 by numerous spot-welds 14. In the fabrication of the door one panel is welded to the corrugation 13 and then the other panel. When the second panel is welded the open space between the panels may be temporarily filled with a conductive agent in order to permit the welding operation.

A re-inforcing rim strip 15, as best shown in the enlarged detail Figures 4 and 5, is applied around the edge of the panel 11 and secured thereto by means of a seam-weld 16. In the fabrication of the door the strip 15 and the other

elements of the frame hereinafter described are formed in segments and the segments butt-welded together to form a continuous member. Around the edge of the panel 12 is secured a continuous rear angle member 17. The members 15 and 17 may be secured to their respective panels before the same are welded to the corrugations 13. The corrugations 13 are co-extensive with the panel 12 and the panel 11 projects past the corrugations 13.

In order to seal the space between the panels 11 and 12 a continuous sealing angle member 18 is applied around the edge of the door. The member 18 is welded to the re-inforcement 17 and to the projecting portion of the panel 11. In this way the body of the door is rendered airtight and watertight. Furthermore, since the panels 11 and 12 are rigidly secured to the corrugations 13, the door is waterproof even though one panel 20 were to be punctured. In order to cause a leak through the body of the door it would be necessary to puncture both panels and the corrugations 13.

Around the edge of the panel 12 is secured a channel member 19 and opposite the member 19 is secured a gasket retaining strip 20 which is carried by the sealing member 18. Disposed in the annular recess formed by the members 19 and 20 is a continuous gasket 21 which may be formed 30 of rubber or other suitable composition. When the gasket 21 is applied to the door it is substantially rectangular in cross-section. When the door is in closed position as shown in Figures 3, 4 and 5, a detent 22 is formed in the gasket 21 by 35 pressure thereof against a flange 23 of an L-shaped frame 24. This forms a seal between the door and the frame. As previously stated, the frame 24 and all of the other continuous members surrounding the door are pre-formed in 40 segments and butt-welded together. The frame 24 is secured to the bulkhead 25 around the opening formed therein to receive the door.

The door is carried on hinges which have a hinge pad 26 secured to the frame 24 and the hinge blade 27 secured to the door near the edge thereof. The hinges are secured, as are all other metal parts, by appropriate welds. A hinge pin 28 is provided to hold the two parts of the hinge together and the opening to receive the pin 28 is enlarged to permit movement of the hinge blade 27 with relation to the pad 26 when the gasket 21 is forced against the flange 23 by the pressure members hereinafter described.

In order to force the gasket 21 into sealing contact with the flange 23 a number of pressure members are provided around the door. A sleeve 29 is disposed through the frame 24 and is secured thereto by arc welds 30. Carried by the sleeve 29 are threaded bushings 31. A rotatable cylinder 34 is carried by the bushings 31 and is provided with an extending handle 33. The under side of the handle 33 is formed with an inclined contact face 32 adapted to ride against a keeper plate 35 carried by the door. The keeper plate 35 is provided with an inclined face corresponding to the incline of the contact face 32 so that when the handle 33 is operated increasing pressure will be applied against the plate 35 thus forcing the gasket 21 against the flange 23.

The inner or lower end of the cylinder 34 is squared at 36 to receive an inner handle 37 which is secured in place by means of a retaining nut 38. Appropriate washers 39 are disposed at either end of the sleeve 29. It is desirable to pack the sleeve 29 in order to make it airtight, and at the

same time provide a lubricant. Accordingly, a threaded bore 40 is formed in the cylinder 34.

At the upper end of the bore 40 is formed a cross-bore 41 to permit the passage of packing or lubricant. A threaded plunger 42 is carried in the bore 40 and is provided with a slot 43 in the head of the plunger 42, so that the same may be removed or inserted with the aid of a screwdriver. The packing and lubricant may be introduced into the bore 40 in the form of cartridges and forced out through the cross-bore 41 through the pressure of the plunger 42.

In order to maintain the pressure member in either open or closed position, the inner handle 37 has formed therein a recess 44 which carries a spring 45 and a ball 46. When the handle 37 is in the open position the ball 46 is adapted to enter a detent (not shown) in order to prevent casual movement of the handle 37, and its associated parts. It will be clear that the pressure member may be operated by movement of either handle 33 or 37. When the pressure member is in the closed position shown in Figure 3 the resilience of the gasket 21 will maintain the elements 33 and 37 in position.

In Figures 4 and 5 are illustrated the handles and locking means. Plates 47 are secured to the outer surface of the door and carry a handle 48 to permit the opening of the door from the outside. On the inside of the door a channel member 49 is secured to the flange formed by the members 17 and 18, and a handle 50 is secured on the channel member 49. In order to lock the door a hasp plate 51 is secured to the outside thereof and is provided with a liner 52. A hasp link 53 is secured by a staple 54 to the frame 24 and is adapted to surround the liner 52. A pin or lock 55 is disposed through the liner 52 to secure the hasp link 53 in position.

In the construction of vessels having airtight doors separating various compartments, it is necessary to test the compartments and the doors from time to time. For this purpose means are provided whereby air may be pumped into a compartment to test the same. In Figure 6 is illustrated the vent for the test means. A sleeve 56 is secured in the frame 24 and is closed by a cap 57 having a sealing washer 58 held in position by a metallic washer 59 and a stud 60. Retaining collars 61 joined by a chain 62 are disposed on the sleeve 56 and cap 57 to prevent loss of the cap 57 upon removal. When it is desired to make a test the door may be sealed and air under pressure introduced into the compartment through the sleeve 56.

The keeper plates 35 have their faces inclined in a direction so that the handles 33 are operated downwardly in sealing the door. Since all of the handles 33 are operated downwardly a considerable strain on the door is created through the friction set up. In order that such strain may not be borne entirely by the hinges a wedge 63 (Figure 2) is carried by the pressure member 18 at the lowermost point of the door. The wedge 63 rides against the flange 23 of the frame 24. Immediately under the wedge 63 the frame 24 is re-inforced by an inclined member 64 so as to prevent undue strain on the frame at that point.

In Figure 7 is illustrated a cover for a hatch. The structure of the cover itself is identical with the structure previously disclosed, except that the hatch cover may be substantially square instead of rectangular. Since the hatch cover is used in a horizontal position the frame 65 is not angular but is straight and is secured to the deck 75

66 by means of the welds 30. A hinge pad 67 is carried on the frame 65 and a hinge plate 68 is carried by the hatch covers. The usual hinge pin 28 is used to secure the parts together.

5 The particular hatch cover disclosed in Figures 7 and 8 is adapted to be opened only from the top side, and accordingly only handles 48 are provided, which handles are disposed at the corners. A plurality of pressure members are 10 provided around the edge of the door and comprise a yoke 69 secured to the frame 65, which yoke 69 pivotally carries a retaining bolt 70 having a compression nut 71 adapted to seat in a recess 72 of a keeper plate 73 carried by the hatch cover. When it is desired to open the hatch the nut 71 may be loosened and the bolts 15 70 swung on their pivots to clear the keeper plates 73, as shown in the lower left-hand corner of Figure 7.

20 A brace 74 is carried by the under side of the hatch cover and has one end removably secured to an eye 75 which may be carried by the cover also. When the hatch is open the loose end of the brace 74 is swung to a position to engage the frame or the deck to maintain the hatch cover 25 in open position at any desired angle.

25 In Figure 9 is illustrated a modified form of hatch cover adapted to be opened from either side. The physical structure of the cover is the same as the hatch cover disclosed in Figure 7 except that the strips 17 and 15 are made considerably wider so that the pressure members may be disposed therethrough.

30 The pressure member is illustrated in Figure 10 and is a modified form of the pressure member shown in Figure 3. A flanged sleeve 76 is disposed through the hatch cover and is secured in place by a complementary collar 77. The usual bushings 31 are provided which carry the 35 spindle 34. An upper handle 78 is formed as an extension of the spindle 34 and a lower handle 79 is secured to the lower end of the spindle 34 by the nut 38. The handle 79 is provided with an extension 80 having an inclined face 81 adapted to enter a recessed keeper 82, the contact face of which is formed at an angle, and which is carried by the frame 65. Operation of either handle 78 or 79 will enter or remove the extension 80 from the keeper 82 to seal or to unseal 40 the hatch cover. The same means for packing and maintaining the pressure member in open position disclosed in Figure 3 are used in the construction shown in Figure 10.

45 Having thus fully described the invention, what is claimed as new and desired to be secured by Letters Patent is:

1. A closure fabricated from a plurality of parts and formed into a unitary structure by welding comprising a pair of spaced panels, 50 corrugated spacing and re-inforcing means between the panels, re-inforcing members disposed around the edges of the panels, a sealing member between the panels adjacent the edges thereof, complementary gasket retaining strips secured at the edges of the panels and a continuous gasket carried by said retaining strips.

2. A closure fabricated from a plurality of parts and formed into a unitary structure by welding comprising a front panel, a rear panel 55 of less area than the front panel, a corrugated

re-inforcing spacer co-extensive in size with the rear panel disposed between the panels, a re-inforcing rim strip adjacent the edge of the front panel, a re-inforcing L-shaped strip secured at the edge of the rear panel and a right-angle sealing member having one flange secured to the projecting surface of the front panel and the other flange secured to the L-shaped strip on the rear panel.

3. A closure fabricated from a plurality of 10 parts and formed into a unitary structure by welding comprising a front panel, a rear panel of less area than the front panel, a corrugated re-inforcing spacer co-extensive in size with the rear panel disposed between the panels, a re-inforcing rim strip adjacent the edge of the front panel, a re-inforcing L-shaped strip secured at the edge of the rear panel, a right-angle sealing member having one flange secured to the projecting surface of the front panel and the other flange secured to the L-shaped strip on the rear panel, a channel member carried by the front panel, a gasket retainer carried by the sealing member and a gasket carried between the channel member and the gasket retainer. 15

4. A closure comprising a panel portion, a right-angle member formed in segments and butt-welded together to form a continuous rim around the panel portion, a channel member spaced from the right-angle member, a gasket 20 carried between the said two members and a gasket retainer carried by one of the members. 25

5. A closure comprising a panel portion, a right-angle member formed in segments and butt-welded together to form a continuous rim 30 around the panel portion, a channel member spaced from the right-angle member, a gasket carried between the said two members and a gasket retainer carried by one of the members, 35 said retainer being formed with an offset portion 40 to lie against the gasket.

6. A closure comprising a panel portion, a right-angle member formed in segments and butt-welded together to form a continuous rim 45 around the panel portion, a channel member spaced from the right-angle member, a gasket carried between the said two members and a gasket retainer carried by one of the members, 50 said retainer being formed with an offset portion to lie against the gasket and an angular portion adjacent the offset.

7. A closure comprising a panel portion, a right-angle member forming a continuous rim around the panel portion, a channel member spaced from the right-angle member, a gasket 55 carried between the said two members and a gasket retainer carried by one of the members, said retainer being formed with an offset portion to lie against the gasket.

8. A closure comprising a panel portion, a right-angle member forming a continuous rim around the panel portion, a channel member spaced from the right-angle member, a gasket carried between the said two members and a gasket retainer carried by said right-angle member, 65 said retainer being formed with an offset portion to lie against the gasket.
